UNITED STATES PATENT OFFICE.

HENRY R. GUNDLACH, OF BALTIMORE, MARYLAND, ASSIGNOR TO THE UNITED STATES ASPHALT REFINING COMPANY, OF NEW YORK, N. Y., A CORPORATION OF SOUTH DAKOTA.

MEANS FOR FORMING EXPANSION JOINTS IN ROADWAYS.

Application filed February 7, 1922. Serial No. 534,738.

To all whom it may concern:

Be it known that HENRY R. GUNDLACH, a citizen of the United States, residing at Baltimore, in the county of Baltimore and State of Maryland, has invented new and useful Improvements in Means for Forming Expansion Joints in Roadways, of which the following is a specification.

The present invention relates to road construction, and particularly to roads built of concrete and like material. It has particularly to do with the expansion joints of such roadways, and its specific object is to provide a convenient and efficient means for making such joint.

In the building of concrete roadways, it is necessary to make provision for the expansion and contraction of those roadways under changing temperatures. High temperatures cause expansion, which, unless compensated for, will fracture the roadway and result in its breaking up and deterioration. It is customary, therefore, in the making of such roads, to provide, at intervals, expansion joints which will give the necessary compensation and permit the expansion of sections of the road without danger of cracking, with the resultant disintegration which rapidly follows any fracture of the concrete material. Heretofore, it has been proposed to form these expansion joints by placing between the ends of adjacent sections, or the fixed curbing and the concrete bed or roadway, material which will yield under the action of the expanding concrete, and one common method of doing this is by pouring between the ends of adjacent sections or the fixed curbing and the concrete section a yielding material, such as asphalt. This method is not economical, as it requires the constant use of an asphalt pot and fire for keeping the asphalt liquid, and the labor incident to forming the joints in this manner is very considerable.

The purpose of my invention is to provide a joint unit which may be manufactured and sold by the asphalt maker to the road builders, which unit is so constructed that it may be readily handled and quickly placed without danger of distortion under varying temperatures or careless handling, but which will, when properly placed in the

roadway, fulfill all of the requirements necessary for the expansion joint between roadway sections, or between foundation sections of concrete, or between roadway sections or foundation sections and fixed independent curbing.

I accomplish this object by providing a slab or board of asphalt mixture which is reinforced by a core of material of greater rigidity than the asphalt of which the slab is made, this core being molded into the slab and being of such character as to maintain that slab in its finished form, and prevent its distortion or breaking down under the usual temperatures, or under the handling of the ordinary workman.

In order that the development may be clear to those skilled in the art, I have shown in the drawings herewith several embodiments of my invention, but it will be understood that these disclosures are simply illustrative, and in no sense restrictive of the development, as equivalent expedients other than those herein disclosed may be adopted and still be within the range of this development.

In the drawings:

Fig. 1 is a view in side elevation of a slab embodying my invention.

Fig. 2 is a sectional view substantially upon the line 2—2 of Fig. 1.

Fig. 3 is a view similar to Fig. 2, showing a different form of insert or core for the slab.

Fig. 4 shows conventionally a roadway with the expansion joint forming slab in place.

Fig. 5 shows a roadway of different construction, namely, with a concrete base, with the expansion joint forming slab in place.

Fig. 6 is a sectional view illustrating the application of the joint forming means between a roadway and a fixed and independent curbing.

Referring to the drawings by numbers, like numbers indicating like parts in the several views, 10 indicates the slab, which may be made of any suitable dimensions, although an ordinary road work, it may be from six (6) to nine (9) feet in length, six (6) to nine (9) inches in width, and one-half to one inch in thickness.

It will be understood that I do not confine myself, however, to any particular dimensions, as these may be varied, according to the needs of the work and the factor of expansion to be taken care of.

The slab 10 will be formed of an asphalt mixture which may be varied to meet the demands of the work or the requirements, either legal or otherwise, of the particular

10 State or locality where the material is used, the requirements, in different sections of the country, as to penetration, solubility, melting point, and the like, varying considerably.

I preferably use blown asphalt as distin-

15 guished from steam refined asphalt, for the reason that blown asphalt, having the same penetration as steam refined asphalt, has a melting point considerably higher, it having been found that blown asphalt, under the

20 ring and ball test, will stand a temperature of 180° F., whereas steam refined asphalt will stand a temperature, under the same test, of only 130° F.

As indicated in dotted lines in Fig. 1 and 25 in full lines in Fig. 2, the slab 10 is provided with an insert or core 11 of material of greater rigidity than the asphalt, the core 11 being preferably of metal, and, in its simplest form, being a metal sheet of from 20 to 26 30 gauge. The core 11 will be preferably entirely enclosed in the asphalt as shown, it extending lengthwise nearly to the ends of the asphalt slab 10, there being a clearance or covering of asphalt approximately one- 35 half inch at the ends of the core or insert. There will be, at the sides of the core or insert 11, a greater clearance, it being preferable to leave substantially one inch of clear asphalt beyond the sides of the core 11 so 40 that the side edges of the slab 10, which are, of course, exposed to traffic, will not be worn down to the extent that the side edges of the core will be exposed. Preferably, the core 11 will be centrally placed with respect to 45 the thickness of the slab, as this gives a better balanced structure than if the core is asymmetrically placed in the slab.

Slabs constructed as hereinbefore described and as illustrated in the drawings 50 may be manufactured at the plant and shipped in quantities to the point of use without danger of their breaking down or becoming distorted, the core supporting the asphalt covering and retaining it in shape 55 so that it will not warp or curl, but will be always ready for insertion in the roadway as indicated in Fig. 4. As there shown, the slab 10 will be inserted between the adjacent ends of the road sections, and these slabs 60 will be spaced along the roadway at intervals, as often as the conditions may demand or the local requirements may call for.

The permanent form of the slab permits 65 it to be readily handled and placed in position, and when once located, it gives proper

compensation for expansion of the roadway sections. There is a sufficient body of asphalt surrounding the core to take care of the expansion and contraction of the concrete sections of the road, the core, while being of sufficient rigidity to give to and retain the permanent form of the slab, being of such character that it does not interfere with the yielding of that slab under expansion strains.

In Fig. 5 I have shown the slab as applied to a concrete foundation, over which foundation may be laid an asphaltic or otherwise suitable surface.

In Fig. 6 I have illustrated the use of the slab between a separate and fixed curbing and a concrete roadway, it being understood that the slab may be employed wherever it is desirable to compensate for expansion.

In the form of the invention shown in Fig. 3, the slab 12 is provided with a core 13 of fluted or corrugated material, this core 13 being preferably of metal.

The advantage of this corrugated core 13 over the plain core shown in Fig. 2 is that it gives an anchoring relation between the core and the asphalt of the slab, and, furthermore, the corrugated core 13 gives greater rigidity to the slab than does the plain core shown in Fig. 2. A further advantage of the corrugated core 13 is that if excessive expansion should take place and the pressure upon the slab 12 should displace the asphalt more or less completely, the corrugated core 13 would, under this excessive pressure, flatten, and yield sufficiently under the pressure of the road sections to guard against any possible fracture of those road sections, even though the expansion reached the point where there was complete displacement of the asphalt of the slab. Where the corrugated core 13 is used, the peaks of the corrugations will preferably be covered by the asphalt to a depth sufficient to take care of the ordinary expansion, preferably to the extent that the sum of the thicknesses of asphalt on the opposite peaks or high points will be not less than one-half the thickness of the slab.

While I have shown, in Fig. 3, a simple and uniformly corrugated sheet, it will be understood that the sheet may be corrugated, ribbed, or provided with anchoring projections and flutings of different design and still be within the purview of my invention.

By following the invention herein disclosed, I am enabled to provide an expansion joint unit which may be manufactured at the plant readily transported to the point of use, stored until needed, and then handled and placed by unskilled labor without any danger of its breaking down or becoming distorted under handling or under the usual temperatures.

Such changes in matters of design, dimen-

sions or construction as are within the range of mechanical skill are, of course, to be regarded as within my invention.

I claim:

- 5 1. A slab for roadway expansion joints, formed of asphalt, and having a stiffening core of metal with corrugations running longitudinally of the slab to permit expansion widthwise, and spaced from the edges 10 of the slab to provide wearing areas of appreciable width on each side of said core.
2. A slab for roadway expansion joints, formed of asphalt, and having a stiffening core formed of an imperforated metal sheet 15 corrugated longitudinally to form laterally extending anchoring projections.
3. A slab for roadway expansion joints, formed of asphalt, and having a stiffening core formed of an imperforated metal sheet corrugated longitudinally to form laterally 20 extending anchoring projections and permit expansion of said core widthwise of the slab.
4. An expansion joint member for filling 25 the expansion joints of concrete and other

masonry structures consisting of a lateral strip of bituminous material having narrow edge surfaces and comparatively broad side surfaces, a corrugated metal reinforcing member extending longitudinally thereof 30 and spaced away from the side surfaces, the corrugations extending longitudinally of the reinforcing member providing for expansion and contraction transversely to the corrugations.

5. In combination with separated sections of a concrete structure spaced to provide for contraction and expansion of said sections, an expansion joint filling member consisting of a strip of bituminous material having a reinforcing member imbedded therein and spaced away from the surfaces of said bituminous material which engage the concrete, said reinforcing member being of corrugated metal, the corrugations extending in the direction of the length of 40 said member.

In testimony whereof I have hereunto set my hand.

HENRY R. GUNDLACH.
